(57) CLAIM

The ornamental design for a vessel for a candle, as shown and described.

DESCRIPTION

FIG. 1 is a perspective view of a vessel for a candle, illustrating our new design;

FIG. 2 is a front elevational view of the vessel for a candle of FIG. 1;

FIG. 3 is a rear elevational view of the vessel for a candle of FIG. 1;

FIG. 4 is a left elevational view of the vessel for a candle of FIG. 1;

FIG. 5 is a right elevational view of the vessel for a candle of FIG. 1; and,

FIG. 6 is a top plan view of the vessel for a candle of FIG. 1.

The broken lines illustrate environmental structure and form no part of the claimed design.
